UNITED STATES PATENT OFFICE.

WILLIAM G. CARRUTH, OF BROOKLYN, NEW YORK.

SAFETY DEVICE FOR TANKS.

1,372,063.

Specification of Letters Patent. Patented Mar. 22, 1921.

Application filed December 6, 1918, Serial No. 265,590. Renewed August 9, 1920. Serial No. 402,504.

To all whom it may concern:

Be it known that I, WILLIAM G. CARRUTH, a citizen of the United States, residing at Brooklyn, in the county of Kings and State 5 of New York, have invented new and useful Improvements in Safety Devices for Tanks, of which the following is a specification.

This invention relates to improvements in safety devices for tanks, and has particular relation to devices operative in connection with supply tanks for motor vehicles.

The present invention is of the type disclosed in my companion application filed April 25, 1918, Serial No. 230,852, in which 15 the mechanism is designed to serve as an anti-theft structure for the contents of the tank, in that the normal means of access to the tank are closed and locked, as well as a structure by means of which theft of the 20 motor vehicle itself is prevented through preventing supply of fuel to the motor. The structure disclosed in said companion application is designed more particularly to take care of conditions where the movement of 25 the tank contents is under the general systems of operation, such as pressure and gravity feed.

The purpose of the present invention is to 30 amplify the control features of said prior application in several respects: (a) by not only controlling the fuel supply line and the filling opening of the tank, but in addition providing control of the tank drainage opening; (b) extending the safety factors of the 35 companion application to systems operating under the vacuum type or system of fuel transfer; (c) to amplify the latter type or system to reduce the possibility of theft of the machine by providing a drainage action 40 to the excess fuel in the system provided by the normal operation of the latter, thus reducing the amount of free fuel to a minimum; and (d) to amplify the safety factors of this type to include the filling and drainage 45 openings of the tank as well as the fuel supply and drainage lines for the system.

To these and other ends, the nature of which will be readily understood as the invention is hereinafter disclosed, said invention 50 consists in the improved construction and combination of parts hereinafter fully described, illustrated in the accompanying

drawings, and more particularly pointed out in the appended claims.

In the accompanying drawings, in which 55 similar reference characters indicate similar parts in each of the views,—

Figure 1 is a sectional view of a portion of a fuel supply tank, showing my present invention applied thereto, the latter being 60 shown partly in section and partly in elevation.

Fig. 2 is a similar view showing the mechanism of the invention in a different 65 position.

Fig. 3 is a diagrammatic view of portions of a motor vehicle, showing the manner in which a well-known type of vacuum system is installed, the view indicating the drainage connections for the system.

Fig. 4 is a sectional view of the vacuum 70 tank of such system.

As heretofore pointed out, the present invention is more or less an amplification of the invention of the companion application 75 and in illustrating the present invention I have shown it as employing many of the features of the structure of the companion application. For convenience in comparison I have shown in the present disclosure 80 views corresponding more or less to those of the prior application, and as far as possible, the reference characters of similar parts are the same in both disclosures. Before giving a detail description of the 85 changes, I will briefly describe the structure common in both inventions in the particular form illustrating the principles of the inventions.

Referring to Figs. 1 and 2, 10 indicates 90 a supply tank for the liquid fuel, the top and bottom walls being indicated respectively at 10^a and 10^b. 11 indicates the threaded flange depending from wall 10^a of the filling opening of the tank, 12 indicating the 95 removable closure therefor having the threaded flange 12^a, the latter carrying opening 12^b at the proper location, this opening being adapted to register with a similar opening formed in flange 11 when the closure is properly seated.

18 indicates a hollow barrel or casing forming a part of the supporting structure for the operating mechanism of the safety

device, this structure being preferably secured to the under face of wall 10^a. The lower end of barrel 18 is shown as provided with a cap 18^a. Mounted within the barrel is a stem 15, the lower end of which projects through cap 18^a.

10 Stem 15 is secured to a guide and control member 19, as by a threaded connection. Member 19 is shown as provided with a groove 20, a section 21 above the groove having an inclined face 21^a, and a pin 22 above portion 21, said pin extending through wall 10^a.

15 23 indicates a locking bolt mounted in an offset 18^b of the barrel, the bolt having a lateral projection 23^a and a lug 23^b, the latter being adapted to coöperate with groove 20 to lock the stem in an inward position against the tension of a spring 27 mounted 20 on stem 15 between member 19 and cap 18^a. Bolt 23 is adapted to reciprocate in the offset, the movement in one direction being by a spring 24, and in the opposite direction by the actuating member 26^a of a locking 25 structure 26, the latter being shown as of the well-known "Yale" type, the escutcheon being shown as exposed on the outer face of wall 10^a to permit key accessibility. Projection 23^a extends into the path of movement of actuating member 26^a, so that when the latter is moved by the key, bolt 23 will be moved against the action of spring 24; as the parts 23^a and 26^a have no direct connection, the position of bolt 23 will determine 30 the question of activity of member 26^a in the operation of the safety mechanism. As shown, lug 23^b serves as a barrier against movement of stem 15 only when the lug is seated in groove 20 (Fig. 1), and in this 35 position member 26^a becomes active in the operation of the mechanism; when, however, stem 15 is in a different position, as for instance shown in Fig. 2, lug 23^b simply bears on the surface of member 19 so that 40 stem 15 is free to be moved in the direction of its length, lug 23^b simply changing its position as its face rides over the surface of member 19. Hence, the use of a key is required only when the parts are in the 45 position shown in Fig. 1.

50 The normal position of stem 15 is shown in Fig. 2, this being the position of the parts when the vehicle is free to be operated. In this position pin 22 projects above the plane of wall 10^a. To shift the parts to the 55 position shown in Fig. 1, it is necessary only to depress pin 22 manually or otherwise, thus bringing groove 20 and lug 23^b into alignment and permitting the lug to enter 60 the groove and lock the parts in this position. By actuation of member 26^a bolt 23 will be withdrawn, spring 27 then returning the stem to the position of Fig. 2.

65 The means for locking closure 12 to its seat is shown as similar to that of the com-

panion application, locking bolt 29 being movable into opening 12^b in flange 12^a by the action of face 21^a as pin 22 is depressed, this movement being in opposition to spring 32; when the stem shifts to the position of Fig. 2, the movement of face 21^a permits spring 32 to retract bolt 29 thus releasing the closure which can then be unthreaded if desired.

70 One of the improvements provided by the present invention is that of also controlling the movements of the drainage closure for the tank, this closure being shown at 40 and carried by wall 10^b. The closure is provided with a recess or cut-away portion 40^a which, when the closure is threaded to its seat, is aligned with a recess or slot 41^a of flange 41 to which the closure is threaded.

75 Since the contents of the tank may be removed by the removal of closure 40, this possibility of theft is eliminated by locking the closure through the movements of stem 15, this being provided by the use of a bell-crank lever 42, pivotally supported by a bracket 43 carried by barrel 18, one arm— 80 42^a—of lever 42 being operatively connected to an exposed portion of stem 15, the other arm 42^b of the lever extending in such direction and being so positioned that when the stem is depressed, as in Fig. 1, 85 arm 42^b will extend into recess 40^a, thus preventing rotation of the closure during such time as the stem may be in this position, movements of the stem rocking lever 42 on its pivot and shifting arm 42^b out of 90 operative relation to recess 40^a, enabling the closure to be unthreaded if desired.

95 As will be understood this safety feature can be readily employed in connection with the disclosure of the companion application.

100 One of the essential differences of the present invention lies in its use in connection with systems of fluid feed operating under vacuum conditions, an operation in which the contents of the supply tank are withdrawn by vacuum action. For purposes of illustration, a well-known form of such apparatus is shown in Figs. 3 and 4.

105 In this particular form the vacuum is provided by the inspirating action of the motor made effective within a chamber 44^a of a tank 44, said chamber having communication with the interior of the supply tank through a suitable connection, shown 110 in Fig. 3 as in the form of a pipe 45, the latter entering tank 10 and having a tube 45^a projecting downwardly therein to a point adjacent the bottom of tank 10. Suitable control mechanism is employed in tank 44^a 115 by means of which the inspirating action of the motor acts to draw fuel contents into chamber 44^a through pipe 45 by the production of a vacuum in said chamber, the 120 vacuum being broken by the action of the 125

control mechanism breaking of the vacuum permitting contents of chamber 44^a to pass through a valved opening 44^b into a reservoir chamber 44^c which, in turn, has an 5 outlet 44^d leading to the carburetor.

The present invention, to meet the change in the form of the discharge outlet from tank 10 from that disclosed in the companion application, is arranged so that control valve 46 has its seating movement in an upward direction, the valve being carried by a lever 47 mounted on a bracket 48, one end of lever 47 carrying the valve—preferably yieldably—the opposite end of the lever being 10 operatively connected to stem 15, thus translating the downward movement of the stem to an upward movement of the valve and vice versa, proper seating being insured through the yielding support of the valve. 15 Hence, when stem 15 is depressed to provide the locking action to closures 12 and 40, it will also move valve 46 to its seat closing the fuel outlet to the tank—which may be considered as the fuel entrance to 20 the fuel line leading to the carburetor—preventing further delivery of fuel to the fuel line even though an inspirating action be provided by “cranking” the motor.

Another safety feature for providing 25 against theft of the vehicle when the vacuum system is employed, is provided by removal of the contents of reservoir 44^c, this reservoir, during the ordinary operation of the system referred to collecting an excess 30 supply of fuel, this excess insuring a fuel supply for the carburetor for an extended period. The presence of this fuel obviously permits operation of the motor for a considerable period even if valve 46 be closed, 35 and to prevent this provision is made for 40 draining this reservoir when it is desired to place the safety system in operation.

This drainage feature is provided by the use of a separate line 49 leading from the 45 top of tank 10 to a point in the connections leading to the carburetor from reservoir 44^c, these connections having a T-coupling to which line 49 is secured. The tank end of line 49 is provided with a valve seat with 50 which co-operates a valve 50—preferably yieldably—carried at the upper end of a valve supporting member 51 operatively connected to the stem 15, the connection, for convenience, being shown as provided by 55 connecting member 51 to arm 42^a, thus imparting a downward or unseating movement to valve 50 when stem 15 is moved downwardly. Obviously, this connection may be provided otherwise. Member 51 60 may be guided in its movements in any suitable manner, the drawings indicating a bracket 52.

As will be understood, valve 50 is seated when valve 46 is moved from its seat, this 65 being necessary in order that the drainage

line 49 will be closed while the motor is in operation to prevent drainage action when the reserve in reservoir 44^c is essential. When, however, it is desired to apply the safety mechanism, the positions of valves 46 70 and 50 are reversed, closing the supply outlet from tank 10 and opening the drainage line to this tank, so that the contents of the reservoir may be returned to tank 10 and thus not only prevent the contents from being removed but also from being used as a means for moving the motor vehicle to any material extent, the immediate supply for the carburetor available for the succeeding operation being contained in the carburetor 75 line below the T-connection.

Obviously, this drainage feature may be omitted if desired.

While I have herein shown and described ways in which the present invention may be practised, it will be readily understood that variations and modifications thereof may be found necessary or desirable in meeting the various exigencies of use, and I desire to be understood as reserving the right to make 85 any and all such changes or modifications as may be found essential or desirable, in so far as the same may fall within the spirit and scope of the invention as expressed in the accompanying claims when broadly construed.

Having thus described my invention, what I claim as new is:

1. In safety devices for tanks, the combination with a tank having filling and 100 drainage openings and a contents delivery outlet, and independent removable closures for the filling and drainage openings, of means within the tank for concurrently closing the outlet and locking said closures 105 against opening movement.

2. In safety devices for tanks, the combination with a tank having filling and drainage openings and a contents delivery outlet, said filling and drainage openings 110 being located in opposite walls of the tank, and independent removable closures for the filling and drainage openings, of means within the tank for concurrently closing the outlet and locking said closures against 115 opening movement.

3. In safety devices for tanks, the combination with a tank having filling and drainage openings and a contents delivery outlet, and independent removable closures 120 for the filling and drainage openings, of means within the tank for concurrently closing the outlet and locking said closures against opening movement, said means including a reciprocating element movable in 125 one direction to provide such closing and locking activity.

4. In safety devices for tanks, the combination with a tank having filling and drainage openings and a contents delivery outlet, 130

and independent removable closures for the filling and drainage openings, of means within the tank for concurrently closing the outlet and locking said closures against opening movement, said means including a reciprocating element movable in one direction to provide such closing and locking activity, and control mechanism rendered active by said movement to retain such activity.

5. In safety devices for tanks, the combination with a tank having filling and drainage openings and a contents delivery outlet, and independent removable closures for the filling and drainage openings, of means within the tank for concurrently closing the outlet and locking said closures against opening movement, said means including a reciprocating element movable in one direction to provide such closing and locking activity, and control mechanism rendered active by said movement to retain such activity, said mechanism including a releasing structure operative when said element is in such position.

10. In safety devices for tanks, the combination with a tank having filling and drainage openings and a contents delivery outlet, and independent removable closures for the filling and drainage openings, of means within the tank for concurrently closing the outlet and locking said closures against opening movement, said means including a reciprocating element movable in one direction to provide such closing and locking activity, and control mechanism rendered active by said movement to retain such activity, said mechanism including a releasing structure operative solely when said element is in such position.

15. In safety devices for tanks, the combination with a tank having filling and drainage openings and a contents delivery outlet, and independent removable closures for the filling and drainage openings, of means within the tank for concurrently closing the outlet and locking said closures against opening movement, said means including a reciprocating element movable in one direction to provide such closing and locking activity, and control mechanism rendered active by such movement to retain such activity, said mechanism including a key-actuated releasing structure operative solely when said element is in such position.

20. In safety devices for tanks, the combination with a tank having filling and drainage openings and a contents delivery outlet, said filling and drainage openings being located in opposite walls of the tank, and independent removable closures for the filling and drainage openings, of means within the tank for concurrently closing the outlet and locking said closures against opening movement, said means including a reciprocating

25. In safety devices for tanks, the combination with a tank having filling and drainage openings and a contents delivery outlet, said filling and drainage openings being located in opposite walls of the tank, and independent removable closures for the filling and drainage openings, of means within the tank for concurrently closing the outlet and locking said closures against opening movement, said means including a reciprocating element movable in one direction to provide such closing and locking activity and a lever operatively connected to said element and movable into and out of engagement with the drainage opening closure by element movements.

30. In safety devices for tanks, the combination with a tank having filling and drainage openings and a contents delivery outlet, said filling and drainage openings being located in opposite walls of the tank, and independent removable closures for the filling and drainage openings, of means within the tank for concurrently closing the outlet and locking said closures against opening movement, said means including a reciprocating element movable in one direction to provide such closing and locking activity and a pivoted bell-crank lever having one arm operatively connected to said element and another arm active in locking the drainage opening closure.

35. In safety devices for tanks, the combination with a tank having filling and drainage openings and a contents delivery outlet, said filling and drainage openings being located in opposite walls of the tank, and independent removable closures for the filling and drainage openings, of means within the tank for concurrently closing the outlet and locking said closures against opening movement, said means including a casing, a reciprocating element movable therein to provide such closing and locking activity, a bracket carried by the casing, and a pivoted bell-crank lever carried by said bracket and adapted to control the locking of said drainage-opening closure, said lever being operatively connected to said element.

40. In safety devices for tanks wherein the withdrawal of contents is provided by vacuum action, the combination with a tank having an outlet in communication with the vacuum-creating mechanism, of a yieldable valve within the tank for controlling said outlet, and means within the tank for controlling the position of said valve, said means including a reciprocating element, and a pivoted lever carrying said valve and operatively connected to said element.

45. In safety devices for tanks wherein the withdrawal of contents is provided by vacuum action, the combination with a tank having an outlet in communication with the vacuum-creating mechanism, of a yieldable valve within the tank for controlling said outlet, and means within the tank for controlling the position of said valve, said means including a reciprocating element, said valve and element being out of axial alignment, and a pivoted lever carrying said valve and operatively connected to said element.

50. In safety devices for tanks wherein the withdrawal of contents is provided by

vacuum action, the combination with a tank having an outlet in communication with the vacuum-creating mechanism, of a yieldable valve within the tank for controlling said outlet, and means within the tank for controlling the position of said valve, said means including a reciprocating element, and mechanism whereby the movement of said element in one direction will move the 10 valve in an opposite direction to close the outlet.

14. In safety devices for tanks wherein the withdrawal of contents is provided by vacuum action, the combination with a tank 15 having an outlet in communication with the vacuum-creating mechanism, of a yieldable valve within the tank for controlling the outlet, and means within the tank for controlling the position of said valve, said 20 means including a casing within the tank, a reciprocating element movable therein, a bracket carried by the casing, and a lever pivoted to the bracket and carrying the valve, said lever being operatively connected 25 to said element to provide valve movements upon element reciprocation.

15. The combination with a supply tank, and a vacuum system for withdrawing the tank contents for delivery to the point of 30 use, said system including a reservoir for the contents withdrawn and also having an inlet within the tank to receive the contents, of independent connections between the tank and reservoir, and means operative at will 35 for closing said connections when the system is made active in the withdrawal operation and for opening said connections when the system is rendered inactive, whereby reservoir contents will be returned to the 40 tank.

16. The combination with a supply tank, and a vacuum system for withdrawing the tank contents for delivery to the point of use, said system including a reservoir for 45 the contents withdrawn and also having an inlet within the tank to receive the contents, of drainage connections between the reservoir and the tank, and means for concurrently controlling said system inlet and 50 the drainage connections to open one and close the other.

17. The combination with a supply tank, and a vacuum system for withdrawing the tank contents for delivery to the point of use, said system including a reservoir for 55 the contents withdrawn and also having an inlet within the tank to receive the contents, of drainage connections between the reservoir and the tank, and means for concurrently controlling said system inlet and the drainage connections, said means being operative to render the drainage operations inactive when said inlet is open.

18. In safety devices for tanks wherein 60 the withdrawal of contents is provided by

vacuum action and wherein the withdrawal contents are delivered to a reservoir *en route* to the point of use, a supply tank having an outlet in communication with said reservoir, independent drainage connections between 70 the reservoir and the tank, and means within the tank for concurrently controlling the activity of said outlet and the connections.

19. In safety devices for tanks wherein the withdrawal of contents is provided by 75 vacuum action and wherein the withdrawn contents are delivered to a reservoir *en route* to the point of use, a supply tank having an outlet for the tank contents positioned adjacent the bottom of the tank, drainage connections between the reservoir and the tank positioned to deliver the drainage through 80 a drainage outlet adjacent the top of the tank, and means within the tank for concurrently controlling said outlets to maintain 85 one outlet closed when the other is open.

20. In safety devices for tanks wherein the withdrawal of contents is provided by vacuum action and wherein the withdrawn 90 contents are delivered to a reservoir *en route* to the point of use, a supply tank having an outlet for the tank contents positioned adjacent the bottom of the tank, drainage connections between the reservoir and the tank positioned to deliver the drainage through 95 a drainage outlet adjacent the top of the tank, and means within the tank for concurrently controlling said outlets to maintain one outlet closed when the other is open, said means including a valve for each outlet, a reciprocating element within the tank, and mechanism for operatively connecting said valves to said element.

21. In safety devices for tanks wherein the withdrawal of contents is provided by 105 vacuum action and wherein the withdrawn contents are delivered to a reservoir *en route* to the point of use, a supply tank having an outlet for the tank contents positioned adjacent the bottom of the tank, drainage connections between the reservoir and the tank positioned to deliver the drainage through a drainage outlet adjacent the top of the tank, and means within the tank for concurrently 110 controlling said outlets to maintain one outlet closed when the other is open, said means including a valve for each outlet, a reciprocating element within the tank, and mechanism for operatively connecting said valves to said element, said mechanism being operative to unseat one valve concurrently with movement of the other valve to its seat.

22. In safety devices for tanks wherein the withdrawal of contents is provided by 125 vacuum action and wherein the withdrawn contents are delivered to a reservoir *en route* to the point of use, a supply tank having an outlet for the tank contents positioned adjacent the bottom of the tank, drainage connections between the reservoir and the tank 130

- positioned to deliver the drainage through a drainage outlet adjacent the top of the tank, and means within the tank for concurrently controlling said outlets to maintain 5 one outlet closed when the other is open, said means including a reciprocating element within the tank and having a stem, a valve for each outlet, and mechanisms operatively connecting each valve with the 10 stem, one of said mechanisms including a pivoted lever adapted to move the valve in a direction opposite the direction of movement of the element.
23. In safety devices for tanks wherein 15 the withdrawal of contents is provided by vacuum action and wherein the withdrawn contents are delivered to a reservoir *en route* to the point of use, a supply tank having an outlet for the tank contents positioned adjacent the bottom of the tank, drainage connections between the reservoir and the tank positioned to deliver the drainage through a drainage outlet adjacent the top of the tank, and means within the tank for concurrently 25 controlling said outlets to maintain one outlet closed when the other is open, said means including a reciprocating element within the tank and having a stem, a valve for each outlet, and mechanisms operatively connecting each valve with the stem, said mechanisms including a pair of operating levers mounted relatively to the stem to provide movement of one valve in a direction opposite that of the other.
24. In safety devices for tanks wherein 30 the withdrawal of contents is provided by vacuum action and wherein the withdrawn contents are delivered to a reservoir *en route* to the point of use, a supply tank having a filling opening and an outlet in communication with said reservoir, drainage connections between the reservoir and tank, a removable closure for said filling opening, and means within the tank for locking said closure against opening movement and concurrently closing said outlet and opening said drainage connections.
25. In safety devices for tanks wherein 35 the withdrawal of contents is provided by vacuum action and wherein the withdrawn contents are delivered to a reservoir *en route* to the point of use, a supply tank having a filling opening and an outlet in communication with said reservoir, drainage connections between the reservoir and tank, a removable closure for said filling opening, and means within the tank for locking said closure against opening movement and concurrently closing said outlet and opening
- said drainage connections, said means including a reciprocating element movable in one direction to provide such concurrent activity.
26. In safety devices for tanks wherein the withdrawal of contents is provided by 60 vacuum action and wherein the withdrawn contents are delivered to a reservoir *en route* to the point of use, a supply tank having a filling opening and an outlet in communication with said reservoir, drainage connections between the reservoir and tank, a removable closure for said filling opening, and means within the tank for locking said closure against opening movement and concurrently closing said outlet and opening said drainage connections, said means including a reciprocating element movable in one direction to provide such concurrent activity, and control mechanism rendered active by 65 said movement to retain such activity.
27. In safety devices for tanks wherein the withdrawal of contents is provided by vacuum action and wherein the withdrawn contents are delivered to a reservoir *en route* to the point of use, a supply tank having a filling opening and an outlet in communication with said reservoir, drainage connections between the reservoir and tank, a removable closure for said filling opening, and means within the tank for locking said closure against opening movement and concurrently closing said outlet and opening said drainage connections, said means including a reciprocating element movable in one direction to provide such concurrent activity, and control mechanism rendered active by 70 said movement to retain such activity.
28. In safety devices for tanks wherein the withdrawal of contents is provided by vacuum action and whereby the withdrawn contents are delivered to a reservoir *en route* to the point of use, a supply tank having a filling opening and an outlet in communication with said reservoir, drainage connections between the tank and said reservoir and independent of the tank drainage opening, independent removable closures for said filling and drainage openings, and means within the tank for locking said closures against opening movement and concurrently therewith closing said outlet and opening said drainage connections.

In testimony whereof I have hereunto set my hand.

WILLIAM G. CARRUTH.
